TRAIN CONTROL SYSTEM

Original Filed July 18, 1929

FIG. 1.

۲۵۱

INVENTOR
BY *W. H. Hailes*,
Neil H. Weston,
his ATTORNEY

UNITED STATES PATENT OFFICE

WILLIAM D. HAILES, OF ROCHESTER, NEW YORK, ASSIGNOR TO GENERAL RAILWAY SIGNAL COMPANY, OF ROCHESTER, NEW YORK

TRAIN CONTROL SYSTEM

Original application filed July 18, 1929, Serial No. 379,155. Divided and this application filed February 25, 1932. Serial No. 595,127.

This invention relates in general to train control systems, and has more particular reference to a system for controlling cars in classification yards.

5 The present case is a division of applicant's pending application 379,155 filed July 18, 1929 for train control systems.

It is usual in classifying cars in classification yards, to run cars to be classified from a

10 plurality of tracks, to a single track, over a hump and through a retarder, to then run the cars onto the proper classification tracks. In this operation it is desirable to expedite matters as much as possible and, depending on

15 conditions, the cars should be pushed over the hump and through the retarder either faster or slower, or cars on certain incoming tracks should be stopped or backed up in order to facilitate classification. It is therefore desirable to have a ready and certain manner of imparting desired information to the various engineers moving the cars.

With the above and other considerations in view it is proposed in accordance with this 25 invention to provide a cab signal system automatically responsive to coded current placed on the track rails, for imparting the desired information to the engineers moving the cars.

30 Further objects, purposes and characteristic features will appear as the description progresses, reference being made to the accompanying drawing showing, in a diagrammatic form, and in no manner in a limiting sense, one form which the invention can assume. In the drawing.—

Fig. 1 is a view of car-carried apparatus in accordance with this invention.

40 Fig. 2 is a diagrammatic illustration of codes which can be employed in connection with the apparatus of Fig. 1.

In connection with the codes shown diagrammatically in Fig. 2, the code indicating fast ahead in this specific case has two-hundred and forty impulses per minute while the code indicating slow ahead has forty impulses per minute, with the stop code and the back code respectively being constituted by current steady off and current steady on, alternating current being employed in order

to obtain a good inductive effect between the car-carried receivers, to be described below, and the track rails or equivalent members upon which the code impulses are impressed

55 The codes diagrammatically shown in Fig. 2 can be produced in any usual or desired manner as by means of toothed code wheels or the like as shown for example in the parent application 379,155.

Referring now to Fig. 1 there is here shown 60 a car-carried apparatus including receiving coils 29, four in number, one over each track rail ahead of the car axles 30, and one over each track rail behind the car axles 30, whereby to inductively pick up control energy 65 from either track rail regardless of direction of travel. The two receiving coils, over each track rail, are sufficiently spaced to bridge over any dead section in the track rails, whereby at least one of the receiving coils 70 will always be subject to the inductive influence of any control current applied to the rails through a transformer or the like, as for example in the parent case.

75 Energy picked up by the receiving coils 29, is transmitted through a tuned circuit including a condenser 31, to the primary of transformer T¹, the secondary of which is connected to the input side of an amplifier Amp of any usual or desired form, with the 80 output side of amplifier Amp connected to a coding primary relay CPR, having contact fingers 32 and 33. The tuned circuit for the primary of transformer T¹, can be dispensed with if desired, it merely being a refinement 85 to be used, preferably, when the train control current is of a frequency different from the commercial frequencies employed.

90 With the apparatus connected up as just described, relay CPR picks up each time control energy is placed on the track rails, and releases each time it is removed from the track rails, whereby contact fingers 32 and 33 follow the code. With current steady on, relay CPR picks up and stays up, while with 95 current steady off this relay releases and stays down.

100 Contact finger 32 operates to place direct current energy across the lower half, or the upper half, of the primary of transformer

T^2 , and then remove it therefrom, each time it makes and breaks contact with its back point and its front point, the primary of transformer T^2 having connected across it 5 a condenser 34.

In the above described manner, a part of the secondary of transformer T^2 is momentarily energized each time relay CPR picks up and releases, to thereby energize a pick-up circuit for relay CR^4 , through rectifiers Rect and $Rect^1$, whereby to energize relay CR^4 with uni-directional current. The flow of current is through one or the other of the rectifiers, wire 35, relay CR^4 and back 10 through wire 36 to an intermediate tap on the secondary of transformer T^2 .

Relay CR^4 is designed so as to pick up only if supplied with energy at a fast enough rate, and in the present case, is designed to pick 20 up on the 240 per minute code, but not to pick up, or if picked up, to release, on the 40 per minute code.

Also included with relay CR^4 , are relays 25 CR^1 , CR^2 and CR^3 , these four relays constituting a decoding group of relays connected up to selectively respond to the code being received, to thereby selectively energize the cab signal CS which includes, in the 30 present instance, a set of four lamps G, Y, W and B indicating, respectively, to the engineer, fast ahead, slow ahead, stop and back.

Relay CR^2 , as is apparent from the drawing, is energized through contact finger 33 and back point of relay CPR, whereby it 35 picks up on release of relay CPR.

In a similar manner CR^1 is energized through a circuit including contact finger 33 and front point of relay CPR, whereby to pick up when relay CPR picks up.

40 Relay CR^3 is energized through a circuit including contact finger 37 and back point of relay CR^1 , whereby relay CR^3 is up when relay CR^1 is down, and vice versa.

45 All of the decoding relays CR^1 — CR^4 are designed to be slow to release whereby to stay up, when once picked up for a period of time at least equal to the longest off period of train control current occurring in any of the control codes.

50 In the position of the various parts as shown in Fig. 2, the W lamp of cab signal CS is energized through a circuit including contact finger 38 and front point of relay CR^3 . As shown in Fig. 2, the W lamp, indicating stop, is energized in response to a code constituted by train control current being steady off.

55 With current steady off, relay CPR is de-energized, to thereby assume its released position, thus to pick up relay CR^2 , drop relay CR^4 , and also drop relay CR^1 . With relay CR^1 down, relay CR^3 is up. Under these conditions no complete circuit exists for energizing any of the other cab signals B, Y and G.

Assume now that in any desired manner, as for example in the parent case by means of a manual control lever, the fast ahead or G code is placed on the track rails. Relay CPR then picks up and releases at a fast rate to send sufficient energy into relay CR^4 to pick up relay CR^4 and maintain it up. The rapidly vibrating contact finger 33 of relay CPR picks up each of the relays CR^1 and CR^2 and these relays stay up since, as explained above, they are slow to release. With relay CR^1 up, relay CR^3 releases and stays down. The G lamp of cab signal CS is now energized through a circuit including one terminal C of a source of electrical energy, wire 39, lamp G, contact finger 40 and front point of CR^4 , contact finger 41 and front point of CR^2 , contact finger 42 and back point of CR^3 , and contact finger 37 and front point of CR^1 , to the other terminal B+.

If now the code placed on the track rails be the slow ahead or Y code, relays CR^1 , CR^2 pick up and stay up, relay CR^3 releases and stays down, and likewise relay CR^4 releases and stays down. Thus a circuit for energizing the Y lamp of the cab signal, is completed, including contact finger 40 and back point of CR^4 , contact finger 41 and front point of CR^2 , contact finger 42 and back point of CR^3 , and contact finger 37 and front point of CR^1 .

When the code is changed to place current steady on the track rails indicating a back up move, relay CPR is picked up and held up, whereby to de-energize CR^4 and CR^3 and CR^2 and energize CR^1 , whereby to complete an energizing circuit for the B lamp of the cab signal including, a back point of CR^2 , a back point of CR^3 and a front point of CR^1 .

With the invention as described above it is apparent that car-carried means have been provided which selectively respond to the code applied to the track rails to set up distinctive cab signals for advising the engineer how he should move the cars.

It is obvious of course that various different codes can be used and that while the invention has been described in connection with coded alternating current there might also be used coded direct current instead of the alternating current.

The decoding apparatus described above is merely one form to exemplify applicant's invention, it being obvious that other forms of decoders, together with other forms of codes, can be used if desired, as for example the decoders and codes disclosed in the W. D. Hailes application Ser. No. 228,058 filed October 22, 1927 in which coded alternating current is employed.

If coded direct current be employed, in place of the alternating current, codes and receiving and decoding means such as shown

in the W. D. Hailes application, Ser. No. 249,457 filed January 25, 1928 can be used.

The above rather specific description of one form of system embodying the present invention, has been given solely by way of illustration, and is not intended, in any manner whatsoever, in a limiting sense. Obviously, this invention can assume many different physical forms, and is susceptible of numerous modifications, and all such forms and modifications are desired to be included by this invention, as come within the scope of the appended claims.

Having described my invention, I now claim:—

1. A decoder for selectively responding to coded energy and in turn controlling secondary indication circuits, including, a primary relay operable to follow the code by picking up and releasing, a decoding relay energized from the secondary of a transformer the primary of which is energized through front and back points of the primary relay, two decoding relays respectively energized through a front and a back point of the primary relay, and another decoding relay energized through a back point of one of said two decoding relays.

2. A decoder for selectively responding to coded energy and in turn controlling secondary indication circuits, including, a primary relay operable to follow the code by picking up and releasing, a decoding relay energized from the secondary of a transformer the primary of which is energized through front and back points of the primary relay and picking up only above a predetermined rate of operation of the primary relay, two decoding relays respectively energized through a front and a back point of the primary relay, and another decoding relay energized through a back point of one of said two decoding relays, said decoding relays all being slow to release.

3. A decoder for selectively responding to coded energy and in turn controlling secondary indication circuits, including, a primary relay operable to follow the code by alternately picking up and releasing, a decoding relay energized from the secondary of a transformer the primary of which is energized through front and back points of the primary relay, two decoding relays respectively energized through a front and a back point of the primary relay, another decoding relay energized through a back point of one of said two decoding relays, and a plural aspect cab signal controlled selectively by said secondary circuits, said secondary circuits including front and back points of various of said decoding relays.

4. A decoder for selectively responding to coded energy and in turn controlling secondary indication circuits, including, a primary relay operable to follow the code by pick-

ing up and releasing, a decoding relay energized from the secondary of a transformer the primary of which is energized through front and back points of the primary relay and picking up only above a predetermined rate of operation of the primary relay, two decoding relays respectively energized through a front and a back point of the primary relay, another decoding relay energized through a back point of one of said two decoding relays, said decoding relays all being slow to release, and a plural aspect cab signal controlled selectively by said secondary circuits, said secondary circuits including front and back points of various of said decoding relays.

5. A decoding means, comprising a primary relay operable to follow the code by movement of its contact fingers to different positions, a decoding relay energized from the secondary of a transformer the primary of which is energized through different positions of the primary relay, and picking up only above a predetermined rate of operation of the primary relay, other decoding relays energized through different positions of said primary relay, and a further decoding relay energized through a back point of one of said other decoding relays.

6. A decoder for selectively responding to coded energy and in turn controlling secondary indication circuits, including, a primary relay operable to follow the code by alternately moving its controlled contactors to different positions, a decoding relay energized from the secondary of a transformer the primary of which is energized through the different positions of the primary relay, two decoding relays respectively energized through the different positions of the primary relay, and another decoding relay energized through a back point of one of said decoding relays.

In testimony whereof, I affix my signature.

WILLIAM D. HAILES.
